DESIGN FOR A COMBINED PICTURE FRAME AND CLIP

Jacob Tamis, Yonkers, N.Y.

Application October 11, 1944, Serial No. 115,713

Term of patent 3½ years

(Cl. D17—10)

To all whom it may concern:

Be it known that I, Jacob Tamis, a citizen of the United States and a resident of Yonkers, in the county of Westchester and State of New York, have invented a new, original, and ornamental Design for Combined Picture Frame and Clip, of which the following is a specification, reference being had to the accompanying drawing, forming part thereof.

Fig. 1 is a top plan view of a combined picture frame and clip, showing my new design.

Fig. 2 is a side view; and

Fig. 3 is a bottom plan view thereof.

I claim:

The ornamental design for a combined picture frame and clip, substantially as shown.

JACOB TAMIS.
